PICTURE FRAME

Filed Oct. 18, 1927

UNITED STATES PATENT OFFICE.

HENRY E. SCHARLING, OF NUTLEY, NEW JERSEY.

PICTURE FRAME.

Application filed October 18, 1927. Serial No. 226,886.

This invention relates, generally, to improvements in picture frames and backings and to hinge and easel structures therefor; and the invention has reference, more particularly, to a picture frame structure of the easel type which is both light and strong and simple in construction and assembly.

The invention has for its principal object to provide an easel picture frame which can be made of sheet metal, which frame is sturdy and strong and of light weight and which can repeatedly be taken apart and reassembled to take out or change the picture or other sheet mounted therein without impairing the structure or the fit of its parts; and a further object of the invention is to provide an easel and hinge structure in such a frame which also are simple, compact and durable.

Other objects of the invention which reside in several detail features of the structure are not at this time more particularly enumerated but will be clearly understood from the following detailed description of the same.

With the various objects of the invention in view, the same consists, primarily, in the novel arrangements and combinations of parts making up the easel frame structure hereinafter set forth; and, the invention also consists in the details of construction of said parts all of which will be hereinafter more fully described and finally embodied in the claims appended hereto.

The invention is clearly illustrated in the drawings, in which:—

Figure 1 is a side elevation view in mid-section of an easel picture frame made according to and embodying the principles of this invention; Figure 1^a is a sectional view in part showing an alternate construction of certain details of the structure of Figure 1; Figure 2 is a front elevation view, in part cut away, of the structure of Figure 1; Figures 3 and 4 are sectional views taken respectively along the line 3—3 and line 4—4 of Figure 2 and looking in the direction of the arrows; Figure 5 is a side elevation view in mid-section of an alternate embodiment of the invention; Figure 6 is a rear elevation view of a backing member for the structures of Figures 1 and 5; and Figure 7 is a perspective view of part of the back showing hinge elements disassembled.

Similar characters of reference are employed in all of the hereinabove described views, to indicate corresponding parts.

Referring now to said drawings, the reference character 1 indicates a rectangular frame of wood, metal or other material, the sides of which frame are of narrow lateral dimension and are comparatively wide from front to back. About the sides of said frame 1 is folded a decorative covering 2 of cloth such as velvet, or of metal or other suitable material. When the frame 1 itself is of metal the surface thereof can be finished for decorative effects. In the preferred form of the invention, however, a cloth, like velvet, is used because it acts as a binding cushion on other parts fitted thereto and hereinafter fully described. Attached to the front of said frame 1 is the flat face frame 3 which extends in both directions from the edges of said frame 1. A sheet of glass 4 fits within said frame 1 and against the back of said frame 3 and back of this is a sheet of paper or cardboard 5 having a picture or other device which it is desired to expose for view in the frame.

For holding said glass 4 and said picture 5 against the flange of said frame 3 there is provided a backing comprising a plate 6 of sheet metal which has upturned edges 7 formed entirely around it. A filling and stiffening member 8 of light cardboard fits into the pan formed by said plate 6 and its upturned edges and a covering 9 of fabric such as velvet is provided over the outside of plate 6 and over the edges 7 thereof, the velvet being turned over onto said filler board 8 and held securely in place by the sheet of paper 10 pasted over the edges thereof and extending over the intervening spaces within the edges of the turned over fabric. The size of said plate 6 and the thickness of the velvet pieces 2 and 9 and the size of the enclosure of said frame 1 are selected so that the sides of the plate 6 with the velvet covering thereon make a frictional fit with the fabric on the inside faces of said frame 1. This arrangement gives a fit that is permanent to hold the back in place in the frame and a fit that will not loosen up through repeated removal and replacement. It also has the advantage that there are no closing buttons or latches to come

loose or be broken. The metal of plate 6 and said filler 8 combine to make a light and rigid back that will not bend or warp and will maintain a good fit with said frame 1.

5 In the easel structure for supporting the frame on a table a leg 11 of sheet metal has formed at its upper end a hinge loop 12 through which extends a wire 13 which at the ends of said loop 12 bends and extends 10 at right angles to the plane of said leg 11 and thence through holes 14, 14 formed in said plate 6 to the opposite surface where it bends against said surface to hold said loop 12 close against the outside surface of said plate 6, 15 or on the covering thereover. A length of ribbon or cord 15 extends at one end through the horizontal slot 16, formed in leg 11 intermediate its length, and is there turned over and pasted or glued against the outer face of 20 said leg 11. The other end of said ribbon 15 extends through a slot 17 formed in said plate 6 opposite the slot 16 in said leg 11, and this end is turned over against the inner surface of said plate 6 where it is glued in 25 place. The hinge wire 13 and the ribbon 15 are of course assembled to said plate 6 before the filling 8 is put in place. A stiffening member 18 of light wood or cardboard is mounted to the outside of leg 11, preferably by means 30 of a covering of cloth 19 which matches said covering 2 and which is held in place by glueing to the leg 11 and stiffener 18. The end of said ribbon 15 of course can be made to extend through both the leg 11 and the stiffener 18 35 to the outer surface of which latter it is affixed as by glueing.

Referring particularly to Figure 1^a, an alternate embodiment of the invention does not have the face frame 3 but does have fixed thereto in place of said frame 3 the angular frame 20, preferably of metal, which fits about the outer lateral edges of said frame 1 and has the angular flange 21 extending inwardly and serving as a stop for said glass 4 and the picture 5 and the backing behind it. In Figure 5 is shown the back plate 6 fitted with its flanges 7 in frictional contact within the inner edge of said frame 20, as another embodiment of the invention in which all the 45 parts of the frame, back, and easel can be of metal and in which is provided a space within the fitted frame and back for the mounting of a glass front and a picture or other display, or in which a mirror can be mounted.

55 I am aware that some changes, other than those already indicated, may be made in the various arrangements and combinations of the several devices and parts, without departing from the scope of this invention as above described, and as defined in the appended claims. Hence, I do not limit my invention to the exact arrangements and combinations as described in the foregoing specification, nor do I confine myself to the exact

details of the construction of said parts as 65 illustrated in the accompanying drawings.

I claim:

1. In a frame structure for pictures and the like, in combination, a frame element, a back member therefor of metal, and an easel 70 structure comprising a strip of metal turned over to form a loop, a wire extending through said loop and having its ends extending through respective openings in said back and lying flat against the face thereof. 75

2. In a frame structure, in combination, a backing member of sheet metal, an easel leg of sheet metal having a transverse loop formed thereon adjacent a face of said backing, and a wire extending through said loop 80 with its ends extending through openings in said backing and extending along the opposite face thereof.

3. In a frame structure, in combination, a backing member of sheet metal, an easel leg 85 of sheet metal having a transverse loop formed thereon adjacent a face of said backing, a wire extending through said loop with its ends extending through openings in said backing and extending along the opposite 90 face thereof, said leg having an opening intermediate its ends and said backing having an opening approximately opposite thereto, and a flexible ribbon or fabric extending between said backing and leg with its ends 95 through respective ones of said opposite openings where they turn against the structure surface and are affixed.

4. In a frame structure for pictures and the like, a frame having inner surfaces at 100 right angles to the plane of the frame and having a flange extending inwardly from sides of the frame, a covering of fabric over said inner surfaces of the frame, a rigid backing member having inwardly directed peripheral flanges fitting into the space bounded by said inner surfaces of the frame and a covering of fabric secured about the flanges of said backing member, adapted to make a frictional holding contact with the fabric on 105 the inner surfaces of said frame. 110

5. An easel back and frame structure, comprising a sheet of metal having upturned edges thereabout, a filler member of card or wood board or the like on said sheet and extending between said edges, a covering of fabric over said metal sheet on its outer face and edges; an easel leg comprising a piece of sheet metal pivoted to said sheet metal backing and a stiffener of card or wood board 115 on last said sheet metal piece, a covering of fabric over said easel leg; and a frame having an inner opening into which said backing member makes a frictional fit. 120

In testimony, that I claim the invention set 125 forth above I have hereunto set my hand this 23rd day of August, 1927.

HENRY E. SCHARLING.
